[57] ABSTRACT

A baseball game having a gameboard on which is provided a baseball diamond. Playing pieces are utilized and are representative of individual baseball players representing two teams. A scoring pad is included to keep records of the activities of the players. Three dice are utilized as a chance determining device to produce a random output count number which is then looked up in a particular table representing the status of the activities during that inning and from the table specific game information is determined. A separate table is provided for each combination of the number of outs in an inning and the number of runners on base. In order to provide rapid access, the tables may be stored in the memory of a computer. The computer includes a first input for entering the output count; a second input for entering the number of outs, the number of runners on base, and the number of innings; and a display for indicating information corresponding to the output number entered and the number of outs and runners on base. In the accompanying appendix there are provided 23 tables for the 23 different inning situations, with a total of 56 possible numeric combinations on each table corresponding to the 56 possible combinations available.

BASEBALL GAME

BACKGROUND OF THE INVENTION

This invention relates to a game of chance and more particularly to a game involving the rules of baseball.

Numerous types of games of chance are presently available. With such games, a chance determining means, such as dice, roulette, etc. are utilized in order to determine the positioning of players on a gameboard, or such similar routine. One of the main requirements of a game is that it be designed so as to keep the interest of the players.

In many sports games it is the desire of the game to try and duplicate as closely as possible the true situations occurring in the sport. For example, in baseball games, the game should try and duplicate the various types of hits, strategies and various events that occur during the course of a game. The problem with such baseball games is that the number of variations, permutations, and different situations is so great that it is generally impractical, if not actually impossible, to duplicate the actual baseball situation in a game.

For example, the variations involved when a first 25 hitter comes at bat is that he could get one or various types of hits, strikeouts, fly out, or numerous other types of variations. For example, even the particular hit could be to any of various places on the playing field; it could be a bunt, or he might get on base as a result of a wild pitch. Furthermore, until he completes his turn at bat there may be a number of balls and strikes involved.

The situation gets further complicated when second and subsequent players get at bat. Each of their possibilities becomes multiplied by the achievement of the previous batter. For example, the second batter has different 30 options depending upon whether there are men on base, and if so which bases, depending upon how many outs there are, and if so the number of outs, and numerous other variations.

At present, most games which try to use a baseball 40 theme for the game, has a limited number of moves and possibilities for the playing pieces and accordingly, lacks the thrill and excitement of a true baseball game and accordingly, fails to maintain the full interest and attention of the players.

SUMMARY OF THE INVENTION

Accordingly, it is an object of the present invention to provide a game of chance, utilizing a baseball theme and which avoids the aforementioned problems of prior art games.

Another object of the present invention is to provide a baseball game which closely simulates the true action and excitement of an actual baseball game.

Still another object of the present invention is to provide a baseball game which has a complete, thorough, and detailed list of possible occurrences of baseball action depending upon the previous events of the particular inning.

A further object of the present invention is to provide a game of chance utilizing true baseball action as the theme of the game, and permitting the players to have an almost unending list of variations and permutations, possible so as to closely simulate the true action of a baseball game.

Briefly, in accordance with the present invention, there is provided a game including a gameboard on which there is formed a baseball diamond. A plurality of playing pieces are distinctively identified to form two teams of individual baseball players. A scoring pad is provided on which the individual scores of the players are indicated as well as their previous records and averages. A chance determining device is provided which produces a random output count in positive integers of numbers in a base seven system. There is also included a table lookup which provides specified game information corresponding to each output count.

In a particular embodiment of the invention, the chance determining device includes a plurality of individual gaming pieces and in such situation the output count always has a corresponding number of digits equal to the number of individual gaming pieces. In an embodiment of the invention, a computer can be included for storing the table lookup and the particular specified game information will be displayed from the computer.

The aforementioned objects, features and advantages of the invention will, in part, be pointed out with particularity, and will, in part, become obvious from the following more detailed description of the invention, taken in conjunction with the accompanying drawings, which form an integral part thereof.

BRIEF DESCRIPTION OF THE DRAWING

In the drawing:

FIG. 1 is an exploded view showing the various component parts in accordance with the present invention, and

FIG. 2 is an enlarged view of a single sheet from the scoring pad shown in FIG. 1.

In the various figures of the drawing, like reference characters designate like parts.

DESCRIPTION OF THE PREFERRED EMBODIMENT

Referring now to FIG. 1, the present game includes a gameboard shown generally at 10 upon which is formed a baseball diamond shown generally at 12. The baseball diamond includes the usual bases 14, infield 16, outfield 18, pitchers mound 20, homeplate 22, and running lanes 24. The layout is such as to substantially duplicate an actual baseball playing field.

Also included are a number of playing pieces 26 each in the form of a baseball player, and mounted on a base 28 such that the playing piece can be suitably positioned on various locations of the baseball playing field. The 50 playing pieces 26 are divided into two teams and are distinctively identified into the two teams by means of different color pieces or other such designations. The playing pieces can each be identical in shape or, alternately, can each be formed into a shape and position to represent a particular type of player such as a catcher, baseman, fielder, etc.

Three dice 30 are also included. Each of the dice include the usual sequence of numbers from one to six on its various sides. For convenience, a box 32 can be 60 provided with a cover 34 in which is stored the various playing pieces and the three dice. Typically, a total of 40 playing pieces will be included with 20 for each team.

A scoring pad 34 is included on which there are a 65 number of scoring sheets, to be hereinafter described. There is also included an instruction chart 36 which can include all of the tables as will hereinafter be described. A computer 38 can be optionally included. The computer can be any type which includes a storage medium and a display 40. Three input keys 42 are provided to enter three numbers as will hereinafter be explained, and an ON-OFF switch 44 is placed on the computer. The actual computer can be any of the well known storage devices which will display an output corresponding to a given input in accordance with information stored in the storage medium. Such computers, or calculators, are well known in the art.

As is well known, the type of event that can occur in a baseball game often depends upon the state of the inning. For example, with bases empty and nobody out, a batter may decide to try for a hit. However, if there is a runner on one of the bases, the batter may sacrifice in order to advance the runner. Furthermore, the events that occur may differ depending upon whether nobody is out or whether there are already two outs in the inning. The present game accommodates for all these variations. At the same time, it gives sufficient variations in occurrences of baseball events to maintain interest in the game.

The game is played by having each player throw the dice. The numbers that come up on the dice occur by chance and accordingly the dice represent a chance determining device. The numbers on each dice are positive integers and form numbers within a base 7 system due to the fact that they go up to a maximum of 6.

Accordingly, with three dice, three positive integers are provided. Each of these numbers are within the base seven system. By taking the lowest number first, then the second lowest and finally the highest number, a total three digit number in the base seven system formed of positive integers can be obtained.

For example, if the lowest number on the three dice is a 1, a second dice has the number 2, and the third dice displays the number 3, the number represented will be 123. If the numbers are 5, 3, and 6, they would be read as 356. If two numbers are the same, as for example the numbers 5, 5, and 2, they would be read as 255.

For each number, there is an entry provided on a table lookup in accordance with the particular instance in the inning. For example, a first table would be provided for the situation of "bases empty, nobody out." Another table would be provided for the situation of "bases empty, one out." Other tables would be provided for the situation of "bases empty, two outs," "runner on first, nobody out," "runner on first, one out," "runner on second, nobody out," "runner on third, two out," "runners on first and third, one out," "runners on second and third, one out," "bases loaded, nobody out," etc. Specifically, for each of the situations of bases empty, runners on each of the bases, runners on combinations of two of the bases, and runners on all three of the bases, there will be a separate table for a respective one of the situations where there are no outs, one, or two outs.

On each table, there will be provided a series of the numbers from 111, 112, . . . 666, with the numbers increasing in positive integers in the base seven system. It should be noted, that since only positive numbers are utilized zero will not occur in the numbering system.

In the accompanying appendix, there is provided all of the 23 tables for the 23 different inning situations, with a total of 56 possible numeric combinations on each table corresponding to the 56 possible combinations available using the three dice in accordance with the aforementioned sequence.

The attached tables provided in the appendix can be included on the instruction chart 36 provided with the gameboard. Alternately, this information can be stored in memory in the computer 38. When utilizing the computer, the number provided by the three dice would be keypunched to the computer by utilizing the keys 42. The computer would determine the corresponding table and utilize the table to determine the instruction and then display the instruction in the display 40. In order to determine the proper table the computer would keep a tally of the number of outs in each inning, the number of players at bat, and the number of runners on each base. Alternately, additional switches or keys 46 could be provided in order to input the number of outs, the number of runners on base, and the number of innings. The particular circuitry involved is such as is well known in the art, and is easily constructed by one skilled in the art.

In order to start the game, each player can throw out one of the dice and the player with the highest number is the first at bat. In order to utilize the scoring pad, each scoring sheet can have a layout as shown in FIG. 2. The scoring sheet includes indicia on which can be written the names of the two teams which are playing. Then, the batting order can be listed on the left hand column. The position of each player can then be identified and thereafter each of the various times that the individual is at bat is entered in an appropriate column in which is indicated the particular activity that the batter achieved during his time at bat.

In order to simplify the utilization of the scoring sheet, the following set of symbols can be utilized in the baseball game:

1—Pitcher	4—Second Baseman	7—Left Fielder
2—Catcher	5—Third Baseman	8—Center Fielder
3—First Baseman	6—Shortstop	9—Right Fielder
K—Strikeout	—Single	E—Error
BB—Base on Balls	—Double	SB—Stolen Base
HR—Home Run	—Triple	DP—Double Play
O—For Out	B—To Bunt the Ball	Sac—Buntin or Flying Out
HP—Hit by Pitcher	WP—Wild Pitcher	BK—Pitchers' Balk
PB—Passed Ball

When entering the information on the scoring sheet, a single horizontal line on the lower right hand corner would indicate a single, two lines in the upper right hand corner would indicate a double, three lines in the upper left hand corner a triple, and a home run would be indicated in the lower left hand corner. The numbers would be placed in the center and would provide an indication as to where in the playing field the hit occurred.

In order to determine the team's record, the number of games won or lost can be determined as a ratio of the total number of games multiplied. This can be converted into a percentage. Similarly, each individual batter's record can be determined. Usually, this is done by determining the number of hits divided by the number of times at bat. This ratio can also be converted to a percentage. Typically, instead of converting to a percentage, the number is divided by 1,000 and this number is utilized in typical baseball fashion.

Similarly, the record of each individual pitcher can be determined. The number of runs is determined and divided by the total innings pitched completely by a particular pitcher. Then, the result is multiplied by nine in order to determine the efficiency of the completed games. In order to record the number of wins and losses of each pitcher, the number of games won is multiplied by 1,000 and the result is divided by the number of games pitched.

In order to make the game more reminiscent of an actual baseball game, particular names of pitchers can be entered on the scoring card and particular names of teams can be entered directly on the particular playing pieces. In this way, leagues can be set up, and entire series can be played.

There has been disclosed heretofore the best embodiments of the invention presently contemplated. However, it is to be understood that various changes and modifications may be made thereto without departing from the spirit of the invention.

APPENDIX

BASES EMPTY, NOBODY OUT

111.—Deep into left field, going, going and gone, a home run at the 380 feet mark.

112.—Outside and low ball.

113.—Strike called.

114.—Round ball to the pitcher, throws to 1st, out.

224.—Low, ball.

225.—Deep line to center field, going back, going back, 55 and makes the catch against the wall.

226.—Strike called, a fast ball.

233.—Round ball up the middle, base hit to center field.

234.—Low, ball.

235.—Strike called.

236.—Round ball to 3rd, takes it throws to 1st, out.

244.—Base hit to the left field line, ball goes all the way to the wall, and is a stand-up double.

245.—Hard rolling to ss., takes it, throws to 1st, out.

246.—Line to center field and makes the out.

255.—Wild pitch.

256.—Swing and a miss, strike.

266.—Fly ball to left field, waiting and makes the out.

333.—Line shot to right center, ball goes one hup to the wall, runner trying for 3 and is safe A triple.

334.—Outside, ball.

335.—Fly ball to right field, waiting and makes the catch.

336.—Line to left field, 4 steps forward and makes the catch.

344.—Round ball to 2nd, takes it, throws to 1st, a bad throw, runner move to 2nd, error.

345.—Hit by the pitch, dead ball, runner goes to 1st base.

346.—Foul fly to left field, here comes the right fielder and makes the catch.

355.—Slow round ball to ss., he throws to 1st, safe, infield hit.

356.—Hard rolling to ss., takes it, throws to 1st, out.

366.—Short fly to center field, it looks good, looks good, is a base hit.

444.—Long fly to left field, going, going and gone, a home run.

445.—High, ball.

446.—Batter bunt the ball, a foul ball.

455.—Round ball to 1st, takes it, throws to the pitcher, he drops the ball, safe, an error.

456.—Time called by the chief umpire, to clean home play.

466.—Hard line to the pitcher and takes it for the out.

555.—Line shot to right field line, ball goes all the way to the wall, runner trying for 3, and is safe, a triple.

556.—Fly to the infield, 1st baseman calls for it and makes the out.

566.—Low in the dirt, ball.

666.—Deep long fly to center field, going back, going back and is gone, a home run at the 411 feet mark.

BASE EMPTY, ONE OUT

111.—Deep fly to left, going, going, hit against the wall, is a double.

112.—Outside, ball.

113.—Strike called. Swinging.

114.—Line to center field and capture (out).

115.—Rolling to 2nd, long throw to 1st, out.

116.—High, ball.

122.—Hard rolling to left (hit).

123.—Strike called, strike out.

124.—Low, ball.

125.—Rolling to 2nd, throw at 1st, out.

126.—Strike, swinging.

133.—Line drive to center (base hit).

134.—Inside, ball.

135.—Rolling to 1st, pitcher comes to cover, the throw and is out.

136.—Fly to center, waiting and got it (out).

144.—Hard line to right field (base hit).

145.—Wild pitch.

146.—Strike called.

155.—Rolling to 3rd, a bad throw, safe (error).

156.—Fly to right field, out.

166.—Dead ball, batter goes to 1st.

222.—Rolling to 3rd, a bad throw, batter goes to 2nd (error).

 145.—Rolling to 1st base, takes it, steps on base and makes the out. 65
 146.—Fly ball to right field, waiting and makes the catch.

- 155.—Outside, ball.
 156.—Round ball to 3rd, takes it, throws to 1st, out.
 166.—Wild pitch.
 222.—Line shot to left field line, ball goes one hop to the wall, a stand-up double.
 223.—Time called, batter steps out of the batting box.
 224.—Hard round ball to 3rd base, takes it behind 3rd base, a long throw to 1st, out.
 225.—Foul fly to short right field, 1st baseman goes for it and makes the catch. 10
 226.—Swing and a miss, strike.
 233.—High, ball.
 234.—Round ball to 3rd, ball goes thru the hole, base hit. 15
 235.—Line shot to left field, ss. jumps and makes the out, what a play.
 236.—Hard rolling to 1st, takes it, runs, steps on base and makes the out.
 244.—Short fly to center, it looks like it is going to drop for a base hit, and it is a base hit.
 245.—Strike called.
 246.—Round ball to ss., takes it, throws to 1st, out.
 255.—Low, ball.
 256.—Slow round ball to 1st, takes it, throws it to the pitcher and makes the out. 20
 266.—Fly ball to left field, fielder goes 4 steps backward and makes the out.
 333.—Deep hard line to right center, ball goes one hop to the wall, runner is going to 3rd and is safe, a triple. 25
 334.—Round ball to 2nd, takes it, throws to 1st, out.
 335.—Swing and a miss, strike.
 336.—Line shot to 2nd base, takes it in a short bound, throws to 1st, out.
 344.—Slow dribble to 3rd base, here comes 3rd baseman, takes it barehanded, throws to 1st, safe, infield hit.
 345.—Outside, ball.
 346.—Fly ball to right field, waiting and makes the catch. 30
 355.—Line drive to left field line, foul ball.
 356.—Round ball to 2nd, takes it, throws to 1st, out.
 366.—Outside, ball.
 444.—Deep fly to left field, going, going and gone, a home run.
 445.—High fly to 3rd base, under the ball, waiting and makes the out. 35
 446.—Swing and a miss, strike.
 455.—Hard rolling to 3rd, takes it, throws to 1st, out.
 456.—Line shot to right field, base hit.
 466.—High ball, the 4th ball, a walk.
 555.—Hard line to right center, nobody can get to the ball, ball hit the wall, and is a standup triple.
 556.—Fly ball to center field, under the ball, waiting and makes the catch. 40
 566.—Hit by the pitcher, dead ball, runner goes to 1st.
 666.—Deep line into left field, going, going and gone, a home run, at the 380 feet mark. 45

RUNNER ON 1ST, NOBODY OUT

- 60 111.—Deep line to center field, going, going and gone, home run, 2 runs scored.
 112.—Strike called.
 113.—High, ball.
 114.—Fly ball to center field, 1,2,3,4 steps forward and makes the catch.
 115.—Round ball to 1st, takes it, throws to 2nd, out, back to first, out, a double play.
 116.—Swing and a miss, strike. 50

- 122.—Slow round ball to ss., throws to 2nd, safe, to 1st, safe. (fielder choice).
 123.—Wild pitch, runner goes to 2nd base.
 124.—Strike called.
 125.—Hard round ball to 3rd, throws to 2nd, out, to 1st, safe.
 126.—Outside ball, runner goes to 2nd, here comes the throw and is out.
 133.—Line, base hit to left field, runners on 2nd and 3rd.
 134.—Pitcher goes to 1st, out, they got him.
 135.—Swing and a miss, strike.
 136.—Fly ball to left field, waiting and makes the catch.
 144.—Hard line to right field, base hit, ball gets away between the legs, runners on 3rd and 2nd.
 145.—Rolling to the pitcher, throws to 2nd, out.
 146.—Outside, ball.
 155.—Round ball to 3rd, takes it, throws to 2nd, out.
 156.—Strike called.
 166.—Line base hit to right field, runner trying to go to 3rd, the throw and is out on 3rd base.
 222.—Short fly to right field, it looks like a base hit, a base hit it is, ball gets away. Runners on 2nd and 3rd.
 223.—Outside, ball, catcher throws to 1st, they got him out.
 224.—Inside ball, runner goes to 2nd, the throw, but runner returns to 1st, safe.
 225.—Batter bunt the ball, a perfect bunt, a base hit.
 226.—Fly ball to left field, waiting and makes the catch.
 233.—Slow round ball to ss., throws to 1st, out, runner moves to 2nd.
 234.—Swing and a miss, strike, runner goes to 2nd, the throw and is safe, stolen base.
 235.—Line, foul ball to left field.
 236.—Pitcher throws to 1st, safe.
 244.—Round ball to 2nd, ball hit the runner, he is out and a base hit for the batter.
 245.—Line to 1st base, takes it, steps on the base, a double play.
 246.—High, ball 4, a walk.
 255.—Pitcher throws to 1st, they got the runner between bases, 1st baseman drops the ball and runner returns safe to 1st.
 256.—Strike called.
 266.—Slow round ball to ss., takes it, throws to 2nd, out.
 333.—Deep into right center, ball hit the wall, batter is going to 3rd, the throw and is safe, a triple, 1 run scored.
 334.—Round ball to 2nd, throws to ss., out, to 1st base, out, a double play.
 335.—Foul fly to the catcher, under the ball, waiting and makes the catch.
 336.—Outside, ball.
 344.—Hard rolling to 1st, ball gets away between the legs, runners on 1st and 3rd.
 345.—Strike called.
 346.—High fly ball to the infield, 2nd baseman calls for it, waiting and makes the out.
 355.—Pass ball, runner move to 2nd base.
 Swing and a miss, strike.
 366.—Strike called.
 444.—Line shot to left field line, ball goes one hup to the wall, runner from 1st score, a stand-up double.
 445.—Hit and run fails, catcher throws to 1st, out, swing and a miss, strike.
 446.—Inside, ball.
